NOZZLE COVER

Charles D. Besore, 701 Heatherside Road,
Pasadena, Calif.

Filed June 29, 1964, Ser. No. 80,638

Term of patent 14 years

(Cl. D91—1)

FIG. 1.

FIG. 3.

FIG. 2.

FIG. 4.

FIG. 1 is a perspective view of a nozzle cover embodying my design;

FIG. 2 is a side elevational view thereof;

FIG. 3 is an end view thereof taken from the left of FIG. 2; and

FIG. 4 is a bottom plan view thereof taken from below FIG. 2.

I claim:

The ornamental design for a nozzle cover, substantially as shown.
